UNITED STATES PATENT OFFICE.

ARTHUR H. BRANDON, OF TOLEDO, OHIO, ASSIGNOR TO ARTHUR H. BRANDON & COMPANY, OF TOLEDO, OHIO.

PIPE-HANDLING APPARATUS.

1,417,490.

Specification of Letters Patent. Patented May 30, 1922.

Application filed September 20, 1920. Serial No. 411,573.

To all whom it may concern:

Be it known that I, ARTHUR H. BRANDON, a citizen of the United States of America, residing at Toledo, Lucas County, Ohio, 5 have invented new and useful Pipe-Handling Apparatus, of which the following is a specification.

This invention relates to assembling and taking apart of threaded members.

10 This invention has utility when incorporated in apparatus for assembling or taking apart pipe, casing or tubing, especially in vertical lines, as in deep petroleum wells.

Referring to the drawings:

15 Fig. 1 is a side elevation of an embodiment of the invention in operative position in an oil well derrick;

Fig. 2 is a plan view on an enlarged scale of the director or pipe guide of Fig. 1;

20 Fig. 3 is a detail view, partly in section, of the mounting hinge for the director;

Fig. 4 is a side elevation of the section rotating apparatus;

Fig. 5 is a detail view of the door to the 5 apparatus' main frame or mounting;

Fig. 6 is a plan view of the apparatus of Fig. 5; parts being broken away;

25 Fig. 7 is a plan view with parts broken away showing the driving ring of the apparatus;

Fig. 8 is a section through the apparatus' mounting frame at a jaw, and through the driving ring away from a jaw;

Fig. 9 is a section on the line IX-IX, 30 Fig. 7, showing a traveling jaw mounting as to the driving ring;

Fig. 10 is a section on the line X-X, Fig. 9;

Fig. 11 is a section on the line XI-XI, 35 Fig. 7; Fig. 12 is a plan of driving gear without the jaws; Fig. 13 is a plan of the jaw holder for the ring of Fig. 12; and Fig. 14 is a section on the line XIV-XIV, Fig. 13.

40 The derrick 1 is shown as provided with a headache post 2 upon which bolts 3 serve to clamp plates 4, 5. The plate 5 has up-standing hinge pin 6 through block 7 having rib 8 embraced by channel 9 anchored to the 45 block 7 by bolts 10 through slot 11 in the web of the channel 9. The free end of the channel arm 9 carries a U-member 12 anchored to the arm by bolts 13. A pair of slide guide elements 14 are adjustably 50 locked by set screws 15. Eyes 16 of the

member 12 carry a pin 17 to mount a door 18 for swinging to close the U-member 12, when actuated against torsion spring 19 by a pull on flexible line 20 about segmental pulley 21 fast with hinge pin 17 fixed with 60 the door 18.

When the door 18 is swung closed, latch 22 as thrown by spring 23, tends normally to maintain such door closed against the action of the torsion spring 19. A cord or 65 line 24 may be pulled from the station adjacent the line 20, for unlatching the door 18, some 18 feet above the derrick floor.

A pair of ears 25 mounted on the horizontally swingable arm 9, adjacent member 12 70 permit ready connection of link 26 extending to second link 27 of the toggle. This link 27 has extension 28, holding the toggle against falling below horizontal position. Right and left nut or turnbuckle 28' permits adjustment of the toggle for aligning up in position concentric with the well hole in the derrick, at right angles to the adjustment of the length of the arm 9 permitted by the slot 11. Toggle link 27 is pivoted in bearing 75 29 carried by the derrick 1. A flexible line 30 extending upward from toggle joint pin 31, may be brought down adjacent the drop lines 20, 24. A guide 32, adjusted by set screw 33 carried by the door 18 completes 80 85 concentric guide group of this pipe director, which guides are adjustable to take care of pipe diameters over a considerable range.

When, in use, it is desired to set or remove a length of pipe, line 24 may be pulled 90 to open the door 18, and then line 30 pulled to break the toggle and swing the open pipe director or "stabber" clear of position over the well hole. When the next length of pipe has been set, or the unthreaded 95 length is removed, and the line lifted, the director may be swung back into operative position by allowing the line 30 to slack the toggle back to horizontal position; and then the door 18 is pulled 100 closed by line 20, with no adjustment of the guides 14, 32, if the pipe be of the same size. In the handling of the large pipe, which in the Texas field is up to 24" in diameter, this "stabber" or director is 105 readily operated for accurately aligning the uppermost joint or length of pipe.

In practice the curb or derrick floor at the well may be provided with a floor plate or spider ring 34 in which wedges 35 may 110

be dropped to hold a line of pipe by an upper pipe section in suspended position in a well. Such pipe section 36, preferably has its upper threaded end carry a pipe coupling 37, into which the next director 5 coupling pipe section 38 may be engaged.

In completing the assembly or knock-down, especially with the very large sizes of pipe, manual rotation is slow and very arduous, although such might occur with the director. To the end of producing an efficient installation susceptible of fully handling a job with rapidity and requiring but few men, a pipe section rotation apparatus 10 is herein disclosed, which is preferably used in connection with the director, for accurately aligning in avoiding crossing of threads in power rotation of the pipe.

Such apparatus is conveniently in the form 20 of a truck for ready shifting into position over the well in use, and removal therefrom when the pipe elevator, or other work adjacent the well hole, is being operated. To this end rollers 39 have uprights 40 provided with slots 41 engaged by bolts 42 in forming vertically adjustable legs with leg 25 elements 43 downwardly from main frame 44. The height or clearance of the apparatus as to the derrick floor may thus be adjusted.

As a power drive on this truck frame 44 there is shown a vertical steam engine 45 having main shaft 46 therefrom carrying clutch 47 which may be shifted by handle 48 35 to bring pinion 49 into mesh with gear 50 on shaft 51 parallel to shaft 46. This shaft 51 has fast thereon pinion 52 in mesh with gear 53 on shaft 54 aligned with the shaft 46. This shaft 54 has pinion 55 in mesh with 40 gear 56 on upper shaft 57 carrying driving bevel pinion 58. This is the slow speed gear train. For the higher speed of early stages of threading, or the later stages of unthreading, the clutch 47 may so be thrown that the 45 shaft 46 is clutched directly to aligned shaft 54, without the speed reduction through the shaft 51. The bevel pinion 58 is in mesh with sectional bevel gear 59, 60.

The truck frame 44, remote from the 50 power drive, has a U-frame 61, shiftable astride a pipe projecting upward from the well. This main frame or mounting member 61 is provided at the free ends of the legs of the U-portion thereof with pairs of eyes 55 62, which may register with eyes 63 of door 64 to carry at one side a hinge pin 65 and at the other side a removable door locking pin 66. The base of the U-frame has horizontally extending therethrough a flat plate 60 67 inwardly terminating in a pipe gripping jaw 68, which may be radially shifted by bolt 69 through the member 61. A similar opposing jaw is carried by the door 64.

A pair of opposing gripping jaws 68 65 fixed with the mounting 61, 64, constitutes a

first pipe gripping means, which it is preferable shall grip the pipe section 36 below the pipe coupling 37. Any holding strain is thus taken directly by this apparatus, and need not tax the spider 34 and its wedges 35. 70

The U-frame 61 is provided with a top seat 69' and a ledge 70 (Fig. 8). Sectional arc plates 71 may be bolted on this ledge 70 to provide an inwardly extending overhang. Carrying member 72 for the gear section 59, has outwardly extending flange 73 which may rest on the seat 69' of the member 61. Recess 74 of the member 72 over the flange 73 provides an annular channel for receiving the arc plates 71, which may 80 be placed in position before the gear section 60 is assembled with the gear section 59. A bracket or pad 75 is mounted adjacent the free terminus of each leg of the U-gear section carrying member 72. These pads 75 85 provide eyes in registry with eyes of pads 76 carried by gear section 60. Hinge pin 77 and removable locking pin 78 complete the annular knockdown assembly of this driving member. Joint break lines 79, 80, allow 90 for maximum capacity of pipe diameters by the member 59.

These members 72, 60, have each a pair of upstanding guides 81 with opposing vertical grooves 82 (Fig. 10) for coacting with 95 guide ribs 83 of a block 84 having horizontal slot 85 in which is plate 86 radially adjustable by bolt 87 through such block 84 above the slot 85. These plates 86 inwardly terminate in pipe gripping jaws 88 mounted in 100 yokes 89, 90, carried by the respective plates 86. T-heads 91 rising from the blocks 84 have terminal eyes through which extend guide pins 92 above compression helical springs 93. Accordingly the blocks 84 and 105 the jaws 88 carried thereby on the plates 86 as the second rotatable pipe gripping means, are normally urged axially away or upward from the first or fixed pipe gripping jaws 68 of the main or mounting frame 61, 64. 110 Plates 94 (Fig. 9) on the guides 81 limit outward travel of the blocks 84. When a pipe section is directed into a coupling, and the jaws 88 adjusted to such pipe section 38, for gripping, first high speed power rotation 115 through the clutch 47 directly to the shaft 54, will cause these jaws 88 to feed downward regularly with the pipe thread pitch. When the downward limit of feed is approached, the driving may be stopped, the locking pin 78 withdrawn, and the released jaws 88, at once automatically snap upward to the travel limit as determined by the plates 94. The door 60 may then be closed 120 and the driving proceed. When there is 125 slowing up of the motor or engine 45, due to tightness of the joint, the clutch may be shifted for slow speed final tightening. The reverse of these operations occurs when there is to be removal of pipe lines from a well. 130

In order that no slight distortion of the apparatus may detract from aligned relation operations as to the two gripping means—one driving and one fixed, the yokes 89, 90 are provided. The yoke 90 has terminal pivot pins 95 for rods 96, swingable into holding relation with the slots 97 (Fig. 11) in the ends of the yoke 89, as adjusted by nuts 98 to thereby permit a throwing of the jaws 88 into gripping relation, even independently of the adjusting bolts 87. For quick control of these jaws, independently of opening the gear section 60, say for resetting of the jaws 88 by the springs 93, toggle links 99 may be thrown through link 100 by operating hand lever 101. With the yoke 89 thus released, this yoke 89 as well as the yoke 90, will be shifted upward by the springs 93. When the apparatus is used for the unthreading of pipe being taken from a well, the springs 93 are placed on the pins 92 above the heads 91.

In operation, after an elevator has placed a pipe section 36 in position in a coupling 37, the director has its toggle joint 31 lowered to swing the frame 12 concentrically of the well. Door 18 is closed, and the pipe section 38 is thus properly aligned. The power driven thread or pipe driving apparatus is then shifted to position about the pipe 36. Door 64 is closed to cause the first gripping means 68 to act as fixed holding means for the pipe section 36. The rotatable gripping means 59, 60, having the jaws 88 is then swung closed to grip pipe section 38 above the coupling 37. A turning on of the power drive, will allow the pipe 38 to slide through the guides 14, 32, as fed downward by the jaws 88, while the jaws 68 hold the apparatus and pipe 36 fixed. In unthreading, the reverse direction of engine drive is used.

In the instance shown in Fig. 12, the main gear section carrying member 72, has rising therefrom guide stems 102 surrounded by helical compression springs 103, normally urging upward against caps 104, a jaw carrying member 105. The jaw plates 86 as adjusted by screws 87, as to one pair thereof, are carried directly on this member 105 away from the gear 59, 60, and yieldable as to such gear, by the springs 103, to allow for the jaws in gripping the pipe to travel along with the progress of the pipe thread pitch. The third jaw 88, is carried by a gate 106, above gate member 107 of the sectional gear. The gate member 107 is mounted on hinge pin 77 and held closed by latch bolt 108. The jaw carrier gate 106 is hinged by pin 109. Torsion spring 110 tends to throw latch 111 into locking engagement with notch 112 when the gate is closed. In this embodiment the three pipe gripping jaws 88, may follow the pipe as a unit, as all are mounted on the relatively rigidly held mem-

bers 105, 106. Any slight distortion out of alignment of the pipe as to the machine may then not tend to twist the gear sections, and the strength and stability of the structure under even these adverse conditions permit it to respond practically to the heavy duty requirements of deep oil well operations. In the use of this casing machine for taking pipe out of a well, the unthreading of the pipe feeds the gear carried jaws upward. Accordingly for such use, the springs 103 are more conveniently omitted, as upon release of the jaws 88 at the upper limit of unwind, unlatching of the gate 106 at once allows the member 105 to fall by gravity, and closing of the gate 106, at once resets the jaws for a continuation of the unthreading operation, and the upward feeding of the ring 105, 106, during such unthreading. The motor 45 is a simple reversible type of steam engine.

In the running up of pipe, excessive tightening is avoided by the introduction of safety valve 113 in steam line 114 to the motor 45, between main steam valve 115 and the motor. In normal speed of operation of the motor 45, there may be such drop in pressure in the line 114, according to the adjustment of the safety valve 113, that the safety valve will hold, but as the motor slows up due to heavier load, the valve 113 may blow, thereby avoiding too tight threading up of the pipe.

What is claimed and it is desired to secure by Letters Patent is:

1. Means for sustaining a pipe in a well including open sides jaw carrying frame closed for holding the pipe against rotation, and open sides jaw carrying rotatable means rigidly mounted coaxially as to the sustaining means and provided with a pipe grip operable to engage a pipe for rotation as to the held pipe.

2. A suspended pipe holding means, a mounting therefor, and open side jaw means closed for gripping a pipe, said means carried radially by and coaxially of the mounting, and in fixed coaxial position as to the holding means and movable axially relatively to the holding means.

3. A pipe section rotation means including a mounting against lateral movement, a pipe grip fixed as to said mounting, and a second pipe grip carried by the mounting coaxially rigid with the first grip and rotatable relatively thereto.

4. A pipe section rotation apparatus including a mounting, and a pair of concentrically fixed pipe grips relatively axially movable.

5. A pipe section rotation apparatus including a mounting, a pipe grip fixed against movement as to said mounting, and a second rotatable pipe grip movable as to said mounting.

6. A pipe section rotation apparatus, a pipe directing guide axially spaced from the apparatus, and a mounting for the guide independently of the apparatus.
- 5 7. Threaded section rotation apparatus including a mounting, a rotatable section grip carried by the mounting, a slide guide aligned with the grip for directing a threaded section as to the grip, said guide being axially spaced from the mounting, and a second mounting for the guide.
- 10 8. A pipe section rotation apparatus, a throw-out adjustable directing guide axially spaced from the apparatus, and a mounting for the guide independently of the apparatus.
- 15 9. A directing guide for aligning sections in assembling a vertical line of pipe including a hinge support, and a toggle for swinging the guide into operative position as to said support.
- 20 10. A pipe director including a mounting hinge, an arm therefrom, a **U**-member carried by the arm, a door for closing the **U**-member, and adjustable guides carried by the member and door.
- 25 11. A pipe director including a headache post carried hinge, an arm therefrom, a **U**-member carried by the arm having a pair of guides, a door for closing the **U**-member provided with a guide concentrically disposed with the member guides, latch means for freeing the door for opening, flexible means for swinging the door for closing, and an adjustable toggle for swinging the member and door on the hinge into and out of operative position.
- 30 12. A well derrick, and a pipe director mounted therewith for swinging in a horizontal plane into and out of position in alignment with the well.
- 35 13. A well derrick, a pipe director mounted therewith for swinging in a horizontal
- 40 plane into and out of position of well alignment, and a toggle between the derrick and director coacting to lock the director in well 45 aligning position.
- 45 14. A pipe section rotation apparatus including a first pipe grip, a second grip rigidly mounted for maintained axial position, and power means effecting relative rotation 50 between said grips.
- 50 15. A pipe section rotation apparatus including a first pipe grip, a mounting with which said grip is fixed against movement, a second pipe grip rotatable as to the mounting and movable toward or from the first grip, and driving means for the second grip.
- 55 16. A pipe section rotation apparatus including a main sectional frame, first pipe gripping means carried by the frame, a sectional member rotatably mounted on said frame, driving means for rotating the sectional member as to the frame, and second pipe gripping means actuatable by the member and axially movable as to the first pipe 60 gripping means.
- 60 17. A pipe section rotation apparatus including a main **U**-frame, an adjustable pipe gripping jaw carried thereby, a door for the frame, an opposing adjustable pipe gripping jaw carried by the door opposing the frame jaw to provide first holding means, a sectional gear mounted by the frame in position concentric with the first gripping jaws, pipe gripping jaws carried by 70 the gear providing second holding means concentrically disposed as to the first gripping means, axial travel guides for the gear driven jaws as to the first jaws to permit engaged jaws to travel with thread pitch advance, and driving means including a pinion in mesh with said gear.
- 75 In witness whereof I affix my signature.
- 80 ARTHUR H. BRANDON.

Certificate of Correction.

It is hereby certified that in Letters Patent No. 1,417,490, granted May 30, 1922, upon the application of Arthur H. Brandon, of Toledo, Ohio, for an improvement in "Pipe-Handling Apparatus," an error appears in the printed specification requiring correction as follows: Page 3, line 117, claim 3, strike out the words "against lateral movement" and insert the same before the comma and after the word "mounting" in line 118; and that the said Letters Patent should be read with this correction therein that the same may conform to the record of the case in the Patent Office.

Signed and sealed this 20th day of June, A. D., 1922.

[SEAL.]

KARL FENNING,

Acting Commissioner of Patents.
